FCB International Co., Walnut Creek, Cal., brochure entitled "Electric Finder", undated, admitted prior art.

Primary Examiner—Antoine Duval Davis
Attorney, Agent, or Firm—Quarles & Brady LLP[57] **CLAIM**

The ornamental design for an electrical instrument probe tip, as shown and described.

DESCRIPTION

FIG. 1 is a perspective view of an electrical instrument probe tip showing my new design;

FIG. 2 is a right side elevational view thereof, the left side elevational view being a mirror image of FIG. 2;

FIG. 3 is a top elevational view thereof;

FIG. 4 is a bottom elevational view thereof; and,

FIG. 5 is a front elevational view thereof.

The broken line representations of an electrical instrument in FIGS. 1-5 are exemplary and form no part of the claimed design.
